UNITED STATES PATENT OFFICE

LOUIS W. HASSENSALL, OF TOLEDO, OHIO

WATER COOLER

Application filed November 7, 1929. Serial No. 405,440.

This invention relates to a water cooler and more particularly to a device adapted to be submerged in water and by means of which frozen carbon dioxide may be employed as a cooling medium.

One object of the invention is to provide a container for a package of frozen carbon dioxide so constructed that gas escaping through an outlet in its top may pass off to the atmosphere above the normal water line of a cooler and thereby prevent water from entering the container.

Another object of the invention is to provide the container with a cover which may be very easily applied or removed and having means at its upper end whereby the container may be easily lifted from a water cooler for insertion of a new package of carbon dioxide without it being necessary for the operator to dip his hands into the water or thrust a fishing implement downwardly into the water in order to engage the container and remove it.

Another object of the invention is to so form the cover of the container that if placed in a crock over which an inverted water bottle is supported with the neck of the bottle extending into the crock it will not be liable to strike the neck of the bottle and interfere with proper seating of the bottle.

Another object of the invention is to provide improved means for holding the body portion or receptacle forming a portion of the container while a cover is removed or screwed tightly into place.

The invention is illustrated in the accompanying drawings, wherein

Figure 1 is a diagrammatic view illustrating modified embodiments of the invention with the containers submerged at various depths in a water cooler.

Fig. 2 is an enlarged view showing one of the improved containers principally in side elevation and partially in section.

Fig. 3 is a top plan view of the container shown in Fig. 2.

Fig. 4 is a view showing a container engaged with a device for holding the body portion or receptacle thereof stationary while its

cover is removed or screwed tightly into place.

Fig. 5 is a transverse sectional view taken on the line 5—5 of Fig. 4, and

Fig. 6 is a view showing a container disposed in a crock with its cover so shaped that it emerges from water in the crock at one side of the neck of an inverted water bottle supported above the crock.

In Figure 1, there has been shown by diagrams containers, indicated in general by the numerals 1, 2, 3 and 4, each of which consists of a receptacle 5 adapted to receive a package of frozen carbon dioxide compressed into a solid cake. These containers or receptacles may be formed with smooth walls or may be corrugated, as shown at 6 in Figure 2, but it is to be understood that the corrugations may extend vertically instead of circumferentially, as shown, or pressed inwardly instead of outwardly. These corrugations are provided in order to increase the area of the cooling surface presented by the container or receptacle and thereby allow water in a cooler in which the container is placed to be quickly cooled. Each of the containers or receptacles shown in Figure 1 is provided with a removable cap and these caps are preferably threaded upon the receptacles so that they may be easily removed or applied and a water-tight joint formed between the cap and the receptacle to which it is applied. The cap 7 applied to the receptacle 1 is of an elongated conical formation and of such height that when the receptacle is resting upon the bottom of the cooler the upper end of the cap in which an outlet opening is formed will be disposed above the normal water line of the cooler. Therefore, as the carbonic acid gas in the receptacle evaporates, it may escape to the atmosphere above the water in the cooler and there will be no danger of water passing through the cap and into the receptacle. The receptacles 2 and 3

have been shown supported in an elevated position above the bottom of the cooler by means of a convenient support 8 which may be perforated or of an open-work construction so that water may pass through it for contact with the walls of the receptacle and

the caps 9 and 10 of these receptacles are shorter than the cap 7. The cap 9 has a short conical upper portion 11 which projects above the normal water line of the cooler and the cap 10 has its tapered or conical upper portion 12 terminating in a short neck 13 which projects above the water line. The support 14 for the receptacle or container 4 is of greater height than the supports 8 but 10 similarly constructed, and in this form of the invention the upper end of the receptacle extends slightly above the water line and the cap 15 is formed with a flat top or head in the center of which is formed an outlet opening. In each instance a collar 16 is provided about the outlet opening of the cap to reinforce this portion thereof and to this collar is attached a ring or eye 17 adapted to be grasped by the operator when removing an 20 empty container or setting a filled one in place. It will thus be seen that in each instance the container may be removed or set in place without the operator dipping his hand into the water or thrusting a rod or the like having a hook at its end downwardly into the water in order to engage the ring and draw the container upwardly.

In Figure 2, there has been shown an enlarged view of the container, indicated by 30 the numeral 1 in Figure 1. Referring to this figure, it will be seen that the receptacle or body is formed with circumferentially extending corrugations which project outwardly but could project inwardly or extend vertically, as previously explained. This receptacle is open at its top and adjacent its upper end is formed with an outstanding circumferentially extending collar 18 constituting an angular ledge upon which is disposed a sealing gasket 19 and at diametrically opposite sides of the body carrying depending hooks 20. These hooks extend toward each other beneath the flange or collar but terminate in spaced relation to each other. The 40 top or cap 7 of the receptacle has its lower cylindrical portion 21 of such diameter that it fits snugly about the body above the collar 18 and this portion of the top is formed with interrupted threads 22 to engage corresponding threads 23 provided upon the receptacle. An outstanding flange 24 is formed about the lower end of the cap thereby providing a wide surface which bears against the upper face of the gasket 19 when the cap is set in place and turned to engage its threads with the threads of the receptacle. It will thus be seen that when the cap is screwed tightly into place pressure will be applied to the gasket and a water-tight seal provided between the 50 cap and body or receptacle. Therefore, the container may be immersed in water when placed in a cooler and while gas may escape through the outlet opening 24 at the upper end of the cap water will be prevented from sweeping into the receptacle. The collar 16

may be formed integral with the upper end of the cap or formed separate and rigidly fixed thereto in any desired manner and the ring preferably consists of a metal strand bent to assume the desired shape and having its ends passed through the collar and formed with heads at their ends. When the cap is applied, it must be tightly screwed into place, and in order to allow a spanner wrench to be engaged with the cap for tightening or loosening it, there has been provided a lug 25 for engagement by the wrench and lugs 26 spaced from each other about the cap to engage upper and lower faces of the wrench jaw and retain the jaw of the wrench in proper engagement with the lug 25 when in use.

The container shown in Figure 4 corresponds to the one indicated by the numeral 4 in Figure 1 and this container is similar in construction to that shown in Figure 2, except that its body portion or receptacle 5 has not been shown corrugated, although it may be corrugated if so desired and its cap or top 15 is formed with a flat head instead of a tapered or conical upper portion. The head of the cap 15 is formed with a centrally located outlet opening and the collar 16 carrying the ring or eye 17 is secured flat upon the head of the cap about the outlet opening. The cap 15 is threaded upon the upper end of the receptacle the same as the cap shown in Figure 2 and the only difference between this cap and the cap shown in Figure 2 resides in the fact that this cap is formed with a flat head or upper wall instead of being tapered. The receptacle is further provided with sets of hooks 20 corresponding to those shown in Figure 2 so that the receptacle may be disposed in a holder and held stationary so that the cap may be screwed tightly into place or removed.

The holder or stand by means of which the receptacles are to be held stationary while applying or removing the caps is illustrated in Figures 4 and 5 and consists of a cylindrical body 27 which tapers upwardly and at its lower end is formed with a base 28 which closes its lower end and is of such diameter that it projects beyond the stand. Openings 29 are formed in the projecting marginal portions of the base so that fasteners may be passed through it in order to secure the base upon a table or other support. From the upper end of the stand project lugs 30 which extend inwardly and are positioned in diametrically opposed relation to each other. These lugs are of such thickness that they may pass between the companion hooks 20 of each set of hooks extending downwardly from the ledge 18 of the receptacle and are also of such dimensions that after the receptacle has been set into the stand with the lugs disposed between the facing hooks it may be turned in order to dispose the lugs between the ledge and the bill of one hook of 130

each set, as shown in Figure 5. Therefore, the receptacle will be held in the stand and prevented from further turning in one direction and the cover or cap may be very easily loosened or screwed tightly into place by a spanner wrench engaged with the lug 25.

The container shown in Figure 6 is of substantially the same construction as that shown in Figure 2 and corresponding elements are designated by the same reference numerals. The receptacle may have smooth surfaces, as shown, or be corrugated, as previously set forth. The main difference between the container shown in this figure and that of Figure 2 resides in the fact that the tapered upper portion 31 of the cover or cap slopes towards one side instead of being of a true conical form. Therefore, the outlet opening formed in the upper end of the cap is disposed above a side portion of the receptacle and when this container is disposed within a crock 32 of the type used in coolers having a water bottle supported in an inverted position with its neck 33 extending downwardly into the crock the upper end of the cap will be disposed between the neck of the bottle and the walls of the crock where it will be out of the way and not be liable to be struck by the neck of the bottle or interfere with passage of water out of the bottle into the crock. A collar 34, corresponding to the collar 16, is disposed about the upper end of the cap and carries a ring or eye 35, corresponding to the ring 17, and by means of which the container may be easily set in place or removed. The collar not only serves as a carrier for the ring or eye but also constitutes a reinforcement disposed about the upper end of the tapered portion of the cap through which the outlet opening for gas is provided and prevents this portion of the cap being liable to be bent and the outlet opening closed if the caps are not carefully handled. The rings 17 and 35 may have chains or equivalent flexible members connected to them for engagement with a hook or other overhead support and thereby allow the containers to be suspended in a cooler and lowered as the water is drawn out of the same or the eye directly engaged with the overhead support.

Having thus described the invention, I claim:

1. In a water cooler, a container for a cooling medium comprising a receptacle open at its upper end, a closure for the open upper end of said receptacle formed with an outlet opening, a collar surrounding the outlet opening, and an eye carried by said collar and projecting upwardly therefrom and constituting means whereby an empty container may be removed from a cooler and a filled container deposited within the cooler with the receptacle submerged in water and the portion of the closure having the opening therein disposed above the water level.

2. In a water cooler, a container for a cooling medium comprising a receptacle open at its upper end, and a closure for the upper end of said receptacle having a portion extending upwardly and formed with an opening at its upper end whereby the container may be disposed within a cooler with the receptacle submerged and the portion of the closure formed with the outlet above the water level.

3. In a water cooler, a container for a cooling medium comprising a receptacle open at its upper end, a closure for the upper end of said receptacle having a portion extending upwardly and formed with an opening in its upper end whereby the container may be disposed within a cooler with the receptacle submerged and the portion of the closure formed with the outlet above the water level, and means carried by the upwardly extending portion of the cover to reinforce the portion thereof about the opening and facilitate placement and removal of the container.

4. In a water cooler, a container for a cooling medium comprising a receptacle open at its upper end, a closure for the open upper end of said receptacle formed with an outlet opening, and means carried by said closure about the opening to reinforce the closure about the opening and facilitate placement and removal of the container.

5. In a water cooler, a container for a cooling medium comprising a receptacle open at its upper end, and a closure for the upper end of said receptacle having a portion extending upwardly and formed with an opening whereby the container may be disposed within a cooler with the receptacle submerged and the portion of the closure formed with the outlet above the water level, the upwardly extending portion of said closure sloping towards one side whereby its upper end may be disposed at one side of the neck of an inverted water bottle supported above a cooler receiving the container.

6. In a water cooler, a container for a cooling medium comprising a receptacle open at its upper end, a closure for the open upper end of said receptacle formed with an outlet opening, the receptacle having an outstanding gasket supporting ledge spaced from its upper end and the closure fitting about the receptacle and threaded thereon above the ledge and having an outstanding marginal flange adapted to compress a gasket against the ledge and form a tight joint between the receptacle and closure, and sets of hooks extending downwardly from said ledge, the hooks of each set being disposed in spaced and facing relation to each other whereby the receptacle may be set into a support with portions of the support extending between the hooks of each set and the receptacle held stationary while applying or removing a closure.

7. In a water cooler, a container for a cooling medium comprising a receptacle open at its upper end, a closure for the open upper end of said receptacle formed with an outlet opening, the receptacle having an outstanding gasket supporting ledge spaced from its upper end and the closure fitting about the receptacle and threaded thereon above the ledge and having an outstanding marginal flange adapted to compress a gasket against the ledge and form a tight joint between the receptacle and closure, sets of hooks extending downwardly from said ledge, the hooks of each set being disposed in spaced and facing relation to each other, and means to hold said receptacle while applying and removing its closure consisting of a stand adapted to encircle said receptacle beneath the ledge thereof, and lugs extending from said stand and adapted to pass between the hooks and engage one hook of each set to prevent rotation of the receptacle in one direction.

8. In a water cooler, a container for a cooling medium comprising a receptacle open at its upper end, a closure for the open upper end of said receptacle formed with an outlet opening, the receptacle having its upper portion threaded and the closure being fitted about the upper end of the receptacle and threaded thereon, means to form a tight joint between the receptacle and closure, and sets of hooks carried by said receptacle, the hooks of each set being disposed in spaced and facing relation to each other whereby the receptacle may be set into a support with portions of the support extending between the hooks of each set and the receptacle held stationary while applying or removing a closure.

In testimony whereof I affix my signature.
